Edward M. Moller

BY

Wason Fenwick & Lawrence,
ATTORNEY

UNITED STATES PATENT OFFICE.

HERSHEL A. BENEDICT, OF EAST ORANGE, AND EDWARD M. MOLLER, OF JERSEY CITY,
NEW JERSEY.

ANCHOR.

Application filed November 26, 1921. Serial No. 518,078.

To all whom it may concern:

Be it known that we, HERSHEL A. BENEDICT and EDWARD M. MOLLER, citizens of the United States, residing at East Orange and Jersey City, respectively, in the counties of Essex and Hudson and State of New Jersey, have invented certain new and useful Improvements in Anchors; and we do hereby declare the following to be a full, clear, and exact description of the invention, such as will enable others skilled in the art to which it appertains to make and use the same.

This invention relates to improvements in anchors and more particularly to an anchor for the attachment of vacuum oilers in place, as upon the bearing housing of motors, axles, etc., as used upon railway cars or other places. It has recently become customary in railway engineering to provide a vacuum oiler to maintain the wool or other waste in the bearing housing, saturated with oil. Such oilers have been manufactured with cylindrical tanks which are secured directly upon the top of the bearing housing, but difficulty has been encountered in attaching the tank satisfactorily in place.

The objects of the present invention are to provide an improved means of attachment of the vacuum tank to the housing; to prevent the tank from shaking loose; to provide a simple, inexpensive but at the same time very secure means of attachment; to avoid extra parts; to provide for quickly mounting and demounting; to utilize a single attaching device for the tank; to use the same attaching means for both the top of the housing and the tank; to secure a device readily incorporated in tanks and housings now in use, and to obtain other advantages and results as may be brought out in the following description.

Referring to the accompanying drawing in which like numerals of reference indicate similar parts throughout the several views,

Figure 1 is a side elevation of the tank and anchorage bolt mounted in position, the tank being broken away at the anchorage bolt in order to disclose the same; and

Figure 2 is an end view of the same.

In the specific embodiment of the invention illustrated in said drawing, reference numeral 1 indicates the bearing housing

within which is carried as usual the wool or other waste which rests upon the axle or other rotating member and is kept saturated by a wick 2 from a vacuum tank 3 positioned transversely of the housing 1 at the top thereof. As the construction and operation of the tank and vacuum system are not features of the present invention, further description of the same is not deemed necessary. Suffice it to say, that the tank is sealed so as not to admit any foreign matter, and it therefore is imperative that the supporting means for the tank does not in any way disturb the sealing of the tank. Furthermore, the tank is mounted upon the top of the housing in such manner that the interior of the housing is likewise protected against any foreign matter entering the same so that the oil which is fed to the waste will remain clean and serve its purpose effectively.

In order to mount the tank in position, we preferably provide a vertically extending sleeve or tube 4 within the tank reaching from top to bottom of the same and opening through the walls of the tank. This tube 4 may be made integral with the walls of the tank, welded thereto, or otherwise formed or held in place so that the interior of the tube will have no communication whatever with the interior of the tank and yet the tube will extend through the tank. As shown, the tank is cylindrical and the tube is formed integral with the walls thereof, extending diametrically through the middle of the tank. By this construction, a bolt or other means may be inserted through the tube and any loosening of the bolt will not cause any leakage nor otherwise disturb the working of the vacuum system. Preferably a boss 5 is formed at each end of the tube, providing an adequate seat at one end for engagement in a corresponding hole in the top 6 of the bearing housing 1, and providing at the other end a suitable reinforcement and offset for engagement with the lock washer or nut on the bolt.

An anchor bolt 7 is shown in the drawings as having its lower end flattened, as at 8, and as secured by bolts 9 to the bearing housing on the inside of said housing, the bolt projecting upwardly and passing through the tube 4. Said anchor bolt is provided with a lock washer 10 and nut 11 at its top. It will be observed that by tightening down

upon the nut, pressure is exerted against the end of said tube, forcing the lower boss 5 into its seat and positively securing the tank in place. Obviously the attachment of 6 the tank in this manner is not only very simple, but may be conveniently and expeditiously accomplished. The anchor bolt 7 is very readily mounted in position with the top 6 of the housing removed, after which 10 the top is put back upon the housing and then the tank 3 is slid down over the anchor bolt and the nut 11 is then applied and tightened, which therefore accomplishes the purpose with a minimum of 15 operations and maximum of efficiency. Furthermore, it will be noted that the single bolt answers the requirements of both securing the top of the housing in place and securing the vacuum tank in position for inspection or replacement of the waste, the 20 same may be quickly and easily done.

As clearly shown in Figure 2 of the drawing we preferably provide a saddle shaped structure on the upper surface of the top 25 6 within which the tank 3 will seat when placed in position.

While we have shown one embodiment of our invention and described the same for the purpose of definiteness in connection 30 with one particular device, it is to be understood that application of my invention may be extended to other uses and various modifications and changes may be made in the construction and assembly without departing from the spirit or scope of 35 the invention as set forth in the following claims when construed in the light of the prior art.

Having thus described our invention, we 40 claim:

1. In a device of the character described, a tank having a tube closed with respect to the interior of the tank and open at its opposite ends to the exterior of the tank, an anchor bolt of greater length than said tube having means at one end for attaching the same to a bearing housing and arranged and

adapted to project through said tube for securing the tank in place.

2. In a device of the character described, a tank having a tube extending through the same closed with respect to the interior of the tank and open at its opposite ends to the exterior of the tank, an anchor bolt of greater length than said tube having means at one end for attaching the same to a bearing housing or the like and arranged and adapted to project through said tube for securing the tank in place.

3. In combination with a housing, a top for said housing, a tank mounted on the top, and an anchor bolt for securing both the top and tank in place on the housing whereby both may be readily removed and replaced.

4. In combination with a housing, an anchor bolt secured within said housing and projecting upwardly out of the top thereof, a top for said housing, and a tank mounted on said top and secured thereto in fixed relation to the housing by said anchor bolt.

5. In combination with a housing, a top for said housing having an opening therein, a tank positioned upon the said top and having an opening therethrough registering with the opening in said top, and an anchor bolt secured to the said housing and extending through said openings of the top and tank for securing said top and tank in position upon the housing.

6. In combination with a housing, a top for said housing having an opening therein, a tank positioned upon said top, a tube extending vertically through said tank closed with respect to the interior thereof and open at its ends registering with the opening in said top, and an anchor bolt extending through said tube for securing said tank and top in position upon the housing.

In testimony whereof we affix our signatures.

HERSHEL A. BENEDICT,
EDWARD M. MOLLER.
